UNITED STATES PATENT OFFICE.

CHRISTIAN BOLZ, OF BUDAPEST, AUSTRIA-HUNGARY.

APPARATUS FOR OPENING OR CLOSING THE DISCHARGE-OPENINGS OF VERTICAL RETORTS.

972,674.

Specification of Letters Patent. Patented Oct. 11, 1910.

Application filed September 27, 1909. Serial No. 519,845.

To all whom it may concern:

Be it known that I, CHRISTIAN BOLZ, a subject of the German Emperor, residing at Budapest, in the Kingdom of Hungary, have 5 invented certain new and useful Improvements in Apparatus for Opening or Closing the Discharge-Openings of Vertical Retorts or Chambers; and I do hereby declare the following to be a full, clear, and exact description of the invention, such as will enable others skilled in the art to which it 10 pertains to make and use the same.

My invention relates to improvements in apparatus for opening or closing the discharge openings of vertical retorts or chambers, and more particularly to that class of apparatus in which the valves of a plurality of retorts are controlled from a central place. Controlling means of this character are required in retorts, because the room which is 15 below the retorts and above the floor of the oven must not be obstructed by levers, or cranks which would interfere with the removal of the coke discharged from the 20 retorts.

The object of the improvements is to provide an apparatus of this class, in which the driving mechanism can easily and securely be connected to, or disconnected from the 25 valve of the retort.

A further object of the improvements is to provide an apparatus which will clearly indicate, whether or not the said valve is connected to or disconnected from the driving 30 mechanism.

With these objects in view my invention consists of the matters described hereinafter and particularly pointed out in the appended claims.

For the purpose of explaining the invention an example of an apparatus embodying the same has been shown in the accompanying drawings in which the same letters of reference have been used in all the views to 45 indicate corresponding parts.

In said drawings—Figure 1, is a vertical cross-section of the lower part of an oven comprising two sets of retorts, and of the valve controlling mechanism, and Fig. 2, is 50 a vertical cross-section of Fig. 1 taken on the line 2—2 and showing a side view of the driving apparatus.

As shown in the said drawings, 1 and 1' indicate two sets of vertical retorts the valves 55 3 and 3' of which are controlled by the same

apparatus. The said valves are in the form of lids which are secured to sleeves 4 and 4' pivotally mounted in brackets 5, 5 and 5', 5' respectively. The means for opening or closing the said valves consist of a rotary 60 and longitudinally slideable shaft 6, one for each pair of retorts 1 and 1', which shaft extends through the sleeves 4 and 4' and is further supported in brackets 7, 7. As shown the sleeves 4 and 4' are formed with clutch 65 teeth 8, and 8' and the shaft 6 has clutch members 9 and 9' secured thereto and adapted to coöperate with the teeth 8 and 8' so as to form positive clutches. As shown in Fig. 1, the clutch members 9 and 9' are so 70 arranged relatively to each other and to the teeth 8 and 8', that by shifting the shaft 6 either the clutch 8, 9 or the clutch 8', 9' is closed, or both clutches are open, so that either the valve 3 or 3' is opened or closed 75 by the shaft 6, or both are unaffected by the rotation of said shaft.

The means for shifting the shaft 6 longitudinally of its axis consists of a screw spindle 10 mounted in a screw-threaded 80 bracket 11 and loosely engaging the front end of the said shaft 6. As shown the connection between the shaft 6 and the spindle 10 consists of collars 12 and 13 made integral respectively with the spindle 10 and 85 the shaft 6. To the shaft 6 there is secured a sleeve 14 embracing the collar 12 with an internal flange. By rotating the spindle 10 and thereby moving the same axially in either direction, the shaft 6 is shifted 90 accordingly, while the said spindle does not interfere with the rotation of the shaft. The spindle can be rotated in either direction by means of a chain wheel 15 operated by a chain 16. It will readily be understood, that 95 a shifting mechanism of the character described sufficient friction is provided to prevent said spindle 10 from rotating on the rotation of the said shaft 6, so that special means for holding the shaft 6 in its position 100 are not required. By thus avoiding a special locking mechanism and its leverage an apparatus of simple and reliable construction is provided. In the preferred form of the apparatus, the chain wheel 18 carries a 105 mark indicating the position of the valves 3 and 3', so that the workman can always see whether or not the said valve is completely closed or opened.

A further feature of the invention relates 110

to the mechanism for rotating the shaft 6. And the object of this part of my invention is to provide a simple driving mechanism for the shaft 6, which will be independent of the expansion of the oven by the heat. For this purpose the driving mechanism consists of a rope or belt gearing.

As shown in Figs. 1 and 2, on each of the shafts 6 and on the front side of the oven a pulley 17 is mounted which is normally free to rotate on said shaft. A screw 32 provided in the bottom plate of the oven engages in a circumferential groove made in a cylindrical flange of the pulley, so as to lock the same against lateral displacement. Thereby the pulley is prevented from following the axial movement of the shaft 6. The hub of each of said pulleys is formed with clutch teeth 18 and 18' adapted to operate with clutch members 19 and 19' secured to the shaft 6 on both sides of the hub of the pulley. The clutch members 19 and 19' are so arranged relatively to each other and to the teeth 18 and 18', that by shifting the shaft 6 with the clutch members 19, 19' and 9, 9' either the clutches 19, 18 and 9, 8, or the clutches 19', 18' and 9', 8' are simultaneously closed.

The pulleys 17 are rotated by rods 20 and 20' slidably supported between rollers 21, 21 and 21', 21' respectively. Said rods are adapted to be reciprocated in opposite directions by means of a crank disk 22 to which they are connected by links 23 and 23'. The latter are connected to the crank disk at diametrically opposite points, so that upon rotation of the said disk the rods 20 and 20' are shifted the same distance, but in opposite directions. Each of the pulleys 17 is connected at its circumference to both rods 20 and 20' by means of flexible members, such as ropes 24 and 24' adjustably attached to the rods by means of screws 25 and 25' respectively. The crank disk 22 can be rotated by a crank 26 operatively connected therewith by a chain 27 and chain wheels 28, 29 and it can be locked in its closing or opening position by means of a weighted crank 30.

As appears from the drawings, upon operation of the crank 26 the rods 20 and 20' are shifted in opposite directions, and such shifting movement is transmitted, through the ropes 24 and 24', to the pulleys 17 which are thereby rotated in one or the other direction. The rotary movement of the pulleys is transmitted to the valves 3 or 3' which are thereby opened or closed according to the direction of the rotation of the crank 26.

An important feature of my invention resides in the use of the elastic connecting

members or ropes 24 and 24', which are more simple in construction and operation than toothed racks heretofore used for this purpose. The apparatus can easily be mounted and if necessary be adjusted by means of the screw 25, 25'.

I claim:

1. In an apparatus for opening or closing the valve of a retort, the combination with a longitudinally slidable rotary driving shaft adapted to be coupled to said valve and to close the same by its rotary movement, of an element for shifting said shaft.

2. In an apparatus for opening or closing the valve of a retort, the combination with a longitudinally slidable rotary driving shaft adapted to be coupled to said valve and to close the same by its rotary movement, of a screw spindle for shifting said shaft.

3. In an apparatus for opening or closing the valve of a retort, the combination with a rotary sleeve carrying said valve, and a rotary and longitudinally slidable shaft extending through said sleeve and adapted to be coupled to said sleeve and to close the valve by its rotary movement, of an element for shifting said shaft.

4. In an apparatus for opening or closing the valve of a retort, the combination with a longitudinally slidable rotary driving shaft adapted to be coupled to said valve and to close the same by its rotary movement, of a driving pulley loosely mounted on said shaft, and means to couple said driving pulley to said shaft upon shifting the latter.

5. In an apparatus for opening or closing the valve of a retort, the combination with a longitudinally slidable rotary driving shaft adapted to be coupled to said valve and to close the same by its rotary movement, of a driving pulley on said shaft, a reciprocatory element, and adjustable connecting means between said pulley and reciprocatory element.

6. In an apparatus for opening or closing the valve of a retort, the combination with a longitudinally slidable rotary driving shaft adapted to be coupled to said valve and to close the same by its rotary movement, of a driving pulley on said shaft, a pair of rods adapted to be reciprocated in opposite directions, and flexible and adjustable connecting members between said rods and pulley.

In testimony whereof I hereunto affix my signature in the presence of two witnesses.

CHRISTIAN BOLZ.
